UNITED STATES PATENT OFFICE.

HENRY D'OLIER, JR., OF RUTHERFORD, NEW JERSEY.

REFLECTOR ATTACHMENT.

959,206.

Specification of Letters Patent. Patented May 24, 1910.

Application filed October 7, 1908. Serial No. 456,657.

To all whom it may concern:

Be it known that I, HENRY D'OLIER, JR., a citizen of the United States, residing at Rutherford, in the State of New Jersey, have 5 invented certain new and useful Improvements in Reflector Attachments, of which the following is a specification.

My invention relates to reflector attachments, and particularly for use in connection with electric glow or incandescent 10 lamps.

While it has been quite common to attach a reflector to an electric incandescent lamp, the attachment has been made without due 15 regard for the position of the reflector surface with respect to the light emitting source, with resultant poor economy in the distribution of the reflected light.

It is the object of my invention to provide 20 a reflector attachment for electric lamps which shall combine with simplicity, cheapness and durability, the function of adjusting the reflector with respect to the source of light, so that different distributions of 25 light, within wide limits, may be obtained, and so that it shall be possible, irrespective of differences in dimensions of socket, lamp, reflector, or other parts, that the reflector may be adjusted after it has been attached 30 to the lamp fixture to that position with respect to the light emitting source which shall produce the most efficient reflection, either to secure greatest concentrations of reflected 35 light, or desired dispersion. To this end I provide an attachment for the reflector which allows the reflector to be adjusted longitudinally with respect to the lamp or socket.

My invention resides in the structures 40 hereinafter shown and described.

For an illustration of one of the forms my invention may take, reference is to be had to the accompanying drawing, in which:

Figure 1 is an elevational view of a lamp 45 socket with the reflector supported thereby and adjustable longitudinally, the reflector and the supporting and adjusting means being shown in vertical section. Fig. 2 is an elevational view of one of the adjuster members. Fig. 3 is an elevational view of another of the adjuster members.

Referring to the drawing, a lamp cord C, or other suitable flexible or rigid support, disposed vertically, or at any other angle, 50 supports a lamp socket S, which may have

the usual key K, here shown as one of the standard sockets used at present and having a bead b approximate its lower end. Into the lamp socket may be fitted an incandescent lamp L shown in dotted lines to indicate the position a lamp may take. A resilient ring member R, circumferentially discontinuous, is provided with a bead c adapted to spring over and register with the lamp socket and bead b, and above this bead c the edge of the ring R is turned over, as at d, to hold the resilient wire ring e, also circumferentially discontinuous. This resilient ring e reinforces or stiffens the ring member R causing a more secure attachment 70 between the ring R and the lamp socket. At some distance below the bead c a steep shoulder f is provided to form between it and the lower lip or flange g a deep and substantially flat sided groove to receive the 75 turned-in edge of the upper adjuster member h.

The adjuster member h is preferably cylindrical in form and is adapted to fit inside of the lower adjuster member i having a 80 steep shoulder formation j and the lip or flange k, the reflector or shade member n, having the inside reflecting surface n', being received and held between the shoulder j and the lip k.

On the adjuster member h is a seat or projection l adapted to enter and move in the spiral groove or bead m on the inside of the adjuster member i. The resilient ring member R is snapped into and expands in the 90 upper aperture in the adjuster member h and the ring R may then be snapped into the position shown, the bead c registering with the socket bead b.

To raise or lower the reflector n, so as to 95 bring its reflecting surface n' to a critical or desired height with respect to the light-emitting source of the lamp L, the lower adjuster member i is rotated, as by thumb and finger, causing the member i to move 100 upwardly and downwardly upon the member h due to the action of the groove m upon the projection l. As shown in the drawing, the reflector n is in its lowermost position, but it may be raised a considerable distance 105 by the action just described.

While the engagement of the lip k upon the lamp L may limit the downward travel of the reflector n, such downward travel may be limited by a stop o on the member i 110

engaging with the turned-in top of the adjuster member *h*. After the member *h* has been entered into the member *i*, the stop *o* is bent from the straight position shown in Fig. 3 to the position shown in Fig. 1.

It will be noted that the adjuster member *i* has a relatively large opening at its lower end, thus forming a wide mouth, to permit the parts to assume as low a position as shown with respect to the lamp.

While I have here shown the projection and groove as means for securing longitudinal movement, it is to be understood that any other form of telescopic or longitudinal movement of the parts *h* and *i* may be employed.

It is preferred that the ring member *R*, the adjuster members *h* and *i*, and the reflector or shade member *n*, be made of sheet metal, such as brass, iron or steel, being brought to form by spinning, by pressing in dies, or by any other suitable process.

From the foregoing description, it is apparent that I have provided an attachment for a reflector to an electric lamp fixture which permits the reflector surface to be adjusted within relatively wide limits longitudinally with respect to the lamp or socket.

The reflector *n* is here represented as being a surface of revolution with its axis substantially coaxial with the socket and lamp axis. It is to be understood, however, that other forms of reflector may be employed, and that the adjuster member may be attached to the reflector member at an angle with the axis of the reflector instead of coaxial as shown. In such case, the axis of the reflector would be at an angle with the socket axis, and the reflector may be rotated around the socket axis, such movement of rotation occurring either at the groove between the shoulder *j* and the lip *k* or by the rotation of the member *h* upon the ring *R* at the groove between the steep shouldered bead *f* and the lip *g*.

What I claim is:

1. The combination with an electric lamp socket, of a lamp held thereby, a resilient ring member engaging said socket, an adjuster member supported by said ring member, a second adjuster member having an aperture adapted to receive said lamp, a shade or reflector supported by said second adjuster member, and means permitting telescopic adjustment of said adjuster members upon each other.

2. The combination with an electric lamp socket, of an electric lamp supported thereby, an adjuster member supported upon said lamp socket, a second adjuster member supported upon said first mentioned adjuster member, means permitting telescopic adjustment of said adjuster members with respect to each other, said second adjuster

member having an aperture adapted to receive said lamp, and a shade or reflector mounted upon said second adjuster member.

3. The combination with an electric lamp socket, of a lamp supported thereby, an adjuster member supported upon said socket, a second adjuster member supported by said first mentioned adjuster member, a projection and groove connection between said adjuster members for permitting longitudinal adjustment of said adjuster members upon each other, and a shade or reflector supported upon said second adjuster member.

4. In combination, a reflector or shade member having an aperture therein, an adjuster member supporting said reflector or shade member and having a mouth coaxial with said aperture, a second adjuster member supporting said first mentioned adjuster member and its attached reflector or shade member, said adjuster members adapted to telescope one upon the other for adjusting said shade or reflector member.

5. The combination with a shade or reflector, of means for longitudinally adjusting said reflector or shade comprising two adjuster members supported one upon the other, said shade or reflector secured upon one of said adjuster members, and a projection and groove connection between said adjuster members for permitting said adjuster members to telescope one upon the other.

6. The combination with an electric lamp socket, of a lamp supported thereby, an adjuster member attached to said lamp socket, a second adjuster member supported by said first mentioned adjuster member and having an aperture adapted to receive said lamp, and a reflector or shade supported by said second adjuster member, one of said adjuster members having a spiral groove and the other having a projection engaging in said groove, whereby one of said adjuster members may be adjusted longitudinally on the other.

7. The combination with an electric lamp socket, of a reflector or shade, means for longitudinally adjusting said reflector or shade with respect to said socket comprising a cylindrical adjuster member secured upon said socket, and a second wide mouthed cylindrical adjuster member supported upon said first mentioned adjuster member and movable longitudinally thereon, said reflector or shade supported by said second adjuster member.

8. The combination with an electric lamp socket, of a lamp held thereby, a shade or reflector supported by said lamp socket, means for adjusting said shade or reflector longitudinally with respect to said lamp comprising adjuster members telescoping upon each other, one of said adjuster members supported upon said lamp socket, the other of said adjuster members supported

- upon said first mentioned adjuster member and supporting said shade or reflector, and means for permitting rotation of said shade or reflector about the axis of said socket.
- 5 9. The combination with an electric lamp socket, of a bead thereon, an adjuster member supported by said bead, a second adjuster member supported by said first mentioned adjuster member, means permitting telescopic adjustment of said adjuster members upon each other, and a shade or reflector supported by said second adjuster member.
- 10 10. The combination with an electric lamp socket, of a bead thereon, a member engaging said bead, an adjuster member supported by said bead engaging member, a second adjuster member, a shade or reflector supported by said second member, and means permit-
- ting telescopic adjustment of said adjuster members upon each other.
11. The combination with an electric lamp socket, of a resilient member engaging said socket, an adjuster member supported by said resilient member, a second adjuster member supported by said first mentioned adjuster member and longitudinally adjustable thereon, and a shade or reflector supported by said second adjuster member.
- 20 25 30
In testimony whereof I have hereunto affixed my signature in the presence of the two subscribing witnesses.
